UNITED STATES PATENT OFFICE.

SAMUEL ROSCOE KING, OF PROVIDENCE, RHODE ISLAND.

DESIGN FOR A NURSING-NIPPLE.

SPECIFICATION forming part of Design No. 25,708, dated June 30, 1896.

Application filed April 20, 1896. Serial No. 588,389. Term of patent 14 years.

To all whom it may concern:

Be it known that I, SAMUEL ROSCOE KING, a citizen of the United States, residing at Providence, in the county of Providence and State of Rhode Island, have invented and produced a new and original Design for a Nursing-Nipple, of which the following is a full, clear, and exact description, reference being had to the accompanying drawings, forming part of this specification.

Figure 1 is a perspective view of a nursing-nipple, showing my design. Fig. 2 is a vertical sectional view, the two views being deemed necessary to fully illustrate my design.

The leading feature of my design consists in the truncated end provided with the large hole, the margin of the nipple surrounding the hole being rounded to form a bead.

In the drawings, A indicates the nipple proper. It is bulb-shaped, but does not terminate in a pointed apex, as is usual in nursing-nipples, and is indicated in broken lines in Fig. 2.

B is the neck of the nipple, and C the socket.

The lower end of the socket is surrounded by the bead d.

The socket C is of cylindrical form. At its upper end at e the socket curves inward and to the contracted neck B, from the neck of the nipple curves outward and gradually inward, the larger part of the bulb of the nipple being at f.

The nipple terminates abruptly at g in the blunted end thereof. The opening h is surrounded by the bead j, giving to the nipple the appearance of an open-top vase.

Having thus described my newly-produced design, I claim as new and desire to secure by Letters Patent—

The design for nursing-nipples herein shown and described.

In witness whereof I have hereunto set my hand.

SAMUEL ROSCOE KING.
